US00D957730S

(12) **United States Design Patent** (10) **Patent No.:** **US D957,730 S**
(45) **Date of Patent:** **** Jul. 12, 2022**

(54) **CASE FOR SMOKING ARTICLES**

(71) Applicant: **Todd Wayne Feldman**, New York, NY (US)

(72) Inventor: **Todd Wayne Feldman**, New York, NY (US)

(73) Assignee: **FREEMINDED CORP.**, New York, NY (US)

(**) Term: **15 Years**

(21) Appl. No.: **29/734,576**

(22) Filed: **May 13, 2020**

(51) **LOC (13) Cl.** **26-06**

(52) **U.S. Cl.**

USPC **D27/172**

(58) **Field of Classification Search**

USPC ..... D27/100, 101, 102, 103, 105, 113, 114, D27/118, 125, 127, 128, 137, 138, 142, D27/144, 161, 162, 163, 164, 165, 166, D27/167, 168, 169, 170, 171, 172, 173, D27/174, 175, 176, 177, 178, 179, 180, D27/181, 182, 183, 184, 185, 186, 187, D27/188, 189, 190, 191, 192, 193, 194, D27/195, 196; D23/360, 362; D28/91.1; D24/110, 110.4–110.6, 113, 224; D9/737 CPC A24F 13/02; A24F 13/22; A24F 13/06; A24F 15/18; A24F 15/00; A24F 13/04; A24F 13/08; A24F 7/04; A24F 7/00; A24F 15/12; A24F 13/10; A24F 13/16; A24F 19/10; A24F 19/14; A24F 40/40; A24F 47/00; A24F 13/12; A24F 13/18; A24F 15/20; A24F 40/00

(57) **CLAIM**

The ornamental design for a case for smoking articles, as shown and described.

DESCRIPTION

FIG. 1 is a top front perspective view of the case for smoking articles, showing my new design;

FIG. 2 is a bottom rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view of the case for smoking articles. In the drawings, the broken lines depict portions of the case for smoking articles that form no part of the claimed design.

1 Claim, 6 Drawing Sheets
